UNITED STATES PATENT OFFICE.

AMOS P. STEINER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

AUTOMATIC SIZING DEVICE FOR GRINDING MACHINES.

Application filed May 7, 1925. Serial No. 28,719.

My said invention relates to an automatic sizing device for grinding machines in combination with a feed control for such machines. The predominant object of the invention is to bring the work automatically to the exact size desired without any attention or assistance of the operator. In furtherance of this object I provide means whereby the sizing of the work is effected by a constant fixed weight operated by gravity, uninfluenced by any outside or personal force that would produce varying results. The usual method of measuring work is affected by the personal equation due to variation in the touch or feel of different operators which also varies in the same operator at different times. The action of a spring is also not completely reliable, as this varies in power at different points of deflection. Another object is to provide means whereby two or more sizes can be obtained or measured with the same device, as by one gauging means for the first or rough size and another later-acting one for the finishing size. Others may be added if necessary.

Another object is to provide electrical contacts that have a wide gap when open and make a complete contact very quickly, eliminating the usual slow moving contacts that burn and fuse the contact points, thus rendering the device inaccurate.

Another object is to make the first or roughing cut with a heavy or coarse feed, and when the roughing size is completed, to change automatically to a fine or light feed for reducing slowly to the finished size.

Another object is to provide for a variable amount of time during which the traversing elements of the machine traverse back and forth to bring the work to a round exact size and to grind or spark out and produce a high class finish or polish on the work. This amount of time is easily and quickly adjusted by a small thumb screw or valve.

Another object is to provide for backing the wheel away from the work quickly after the work is finished thus allowing plenty of room for the operator to remove the finished work and put in a new piece. The distance the wheel is fed back is adjustable for different amounts that may be left on the work to be ground off.

Another object is to provide a signal in

the form of a light or bell or other device to notify the operator of the completion of the operation or cycle, so he may give his attention to running two or more machines.

Another object is to provide means whereby operation of the tail stock for removal of the finished work, will return the sizing device and latch it in position in readiness for the next piece to be ground.

Referring to the accompanying drawings, which are made a part hereof and on which similar reference characters indicate similar parts,

Figure 1, is an assembly plan showing the general arrangement,

Figure 2, an assembly plan of the tail stock and the sizing device on a larger scale,

Figure 3, a side elevation of a lever on the tail stock, with parts in section,

Figure 4, a fragmentary side elevation of the tail stock spindle and parts connected thereto,

Figure 5, a side elevation of the sizing device,

Figure 6, a rear elevation of the sizing device,

Figure 7, a horizontal section of the sizing device showing operating parts,

Figure 8, a plan of the wheel feed mechanism,

Figure 9, an end elevation of the wheel feed mechanism,

Figure 10, an enlarged vertical section of the valve mechanism shown in Figure 9, and

Figure 11, a side elevation of the feed reducing bar.

In the drawings reference character 10 indicates a wheel base, 11 a grinding wheel, 12 a tail stock and 13 a piece of work to be ground, the work being supported by work centers 14 or in any other suitable manner. The wheel and work may reciprocate relatively to one another or not, according to circumstances, and the work revolves in the direction of the arrow in Figure 5, all in a manner that is well-known to those familiar with the construction of grinding machines.

As clearly shown in Fig. 2 the sizing device, which is similar in certain respects to that shown in my co-pending application No. 757,279 filed December 20, 1924, is mounted on the tail stock 12 but obviously

the construction could be varied by mounting it on the table or other part of the machine, all without departing from the spirit of the invention. A circuit closer 15 is mounted on a shaft 16 (Figs. 6 and 7) which shaft also carries a gage 15'. The shaft is supported for rocking movement in bearings 17, 17, here shown as ball bearings, said bearings being mounted in recesses in the walls of casing 18. The gage 15' has at its forward end fingers 19 and 20 holding diamonds 21 and 22. These fingers are mounted at different levels for alternate engagement with the work and are adjustable by means of screws 21' held in adjusted position by lock nuts 22'. The gage 15' has a rearwardly extending arm serving as a lever for lifting the diamonds out of position manually when desired.

20. The circuit closer 15 is provided at its free end with a pair of contacts 23 and 24 for closing a pair of electric circuits. The contact 23 operates in conjunction with the upper diamond 21. When the work is reduced sufficiently to allow said diamond to pass under the influence of gravity, the contact 23 moves into engagement with a pair of resilient stationary contacts indicated at 23' (Figs. 5 and 7) closing a circuit by means of which the feed is changed from a roughing to a finishing feed as hereinafter described. When the finishing operation has proceeded sufficiently far the lower diamond also passes the work under the influence of gravity as above described and permits the circuit closer to move thus bringing the contact 24 into engagement with resilient stationary contacts indicated at 24' and closing a second circuit to stop the feed. Circuit closing devices of other types may obviously be substituted for those shown in the drawings.

It will be noted that the diamonds are set at different distances from the work center, the lower diamond being farthest from its center of oscillation and being held at first by the swell or curve of the work below a plane passing through the axis of the work and the axis of the gage 15', the work being of course larger than the desired size. As the work decreases in size the weight of the forwardly extending arms of the gage and the circuit closer (the lower side of Fig. 1 being taken as the front of the machine) acts on the diamonds with a uniform force to cause them to rise until the diamond 21 passes the work closing the first mentioned circuit. Thereafter the same action continues until the diamond 22 passes the work and closes the second circuit, the step-by-step feed reduction being continued as far as desired.

The casing 18 is adjustable toward and from the work by means of a screw 27 having a graduated dial 28 for indicating in

thousandths the position of the casing. A suitable guide for the casing is provided at 25 on the base 26 (Fig. 6).

A latch 29 (Figs. 5 and 6) engages the forwardly extending arm of the gage to hold it and the circuit closer out of working position. Below the circuit closer I have provided a shaft 31 carrying a cam 30 for engagement with a cam face at 30' on the circuit-closer. This shaft also carries a rock-arm 32 (Figs. 4 and 5) connected to the tail stock spindle 33 by a link 33'.

The tail stock has an operating lever 34 (Figs. 2 and 3) having a pin and slot connection at 34' with the tail stock spindle. This lever carries a spring-pressed detent 35 adapted to engage a notch 36 in a fixed plate 37 which detent can be retracted by pressure on the thumb latch 58.

A pull on the lever 34 bringing it into the position indicated in dotted lines at B in Figure 2 moves the work center 14 back to release the work 13. This movement also, by means of link 33' and arm 32 turns the shaft 31 and causes cam 30 to engage the circuit closer 15 at 30', raising it so that the diamonds assume a position below that in Fig. 5 and out of the way of the work. This operation also moves the rearwardly extending arm of the gage to bring it into engagement with the latch 29 by means of which it is held in raised position to maintain the diamonds out of the way of the work. When the lever 34 is moved to release the work, as above described, the detent 35 engages the notch in plate 37 thereby holding the lever in place and consequently holding the work center in retracted position. When the operator has now inserted a new piece of work he has but to press the latch 38 and release the lever whereupon the center enters the work to be ground and holds it in place. The latch 29 may now be caused to release the gage by pressure exerted against the laterally extending pin 39 or the arm may be held up by the latch until the grinding wheel has taken enough of a cut to present a smooth surface for contact by the first diamond 21.

The feeding means for the wheel is shown in Figs. 1, 8, 9, 10, 11 and said means comprises an armlike frame member 40 supporting a ratchet 41. A pawl 42 engages the ratchet said pawl being mounted on a rockarm 43 actuated at appropriate intervals in any suitable manner in the operation of the machine as for instance at the end of each stroke of the reciprocating carriage. A screw 44 limits the movement of the arm in one direction and this screw may be adjusted to vary the length of the stroke and thus change the extent of movement of the ratchet. The feed of the wheel toward the work is controlled in any suitable manner in accordance with the rotation of the ratchet. A detent pawl 45 engages the ratchet to hold

it against reverse movement as it is advanced by the pawl 42. A weight 46 is suspended from the ratchet by means of a cable 47 and this tends to return the ratchet to its original position.

My invention includes means for changing the feeding movement of the wheel in addition to the adjusting means 44, the additional feed change being desirable for changing from a feed such as is desirable for rough grinding to a feed such as is desirable for a finishing action and consisting preferably of a radical reduction in the feed at a single step.

This mechanism comprises a slide bar 48 mounted in a bearing in the frame member 40 and impelled in one direction by a spring 49 (Fig. 8) which tends to throw it into the position indicated in Fig. 11 where the rock-arm is permitted to move to its fullest extent except as limited by the position of the screw 44. This provides a feed suitable, e. g. for rough grinding. When such a change is desired, as for example to a limited feed desirable for finishing grinding, the feed is reduced by diminishing the movement of the arm 43. In the present embodiment of the invention this takes place through the sizing device above described when the work reaches such a size as to permit the diamond 21 to pass and thus closes at 23 the energizing circuit of the magnet 50 through the conductors 51 and 52. The electromagnet thereupon attracts its armature which consists of the enlarged head at the left end of the slide bar 48 and draws the slide bar to the left into a position in which the enlarged end 48' of the bar comes into the path of the rockarm 43 to limit its return movement thus limiting its operative stroke and therefore the feeding movement of the wheel. The extent of change in the arc of oscillation is subject to variation by adjustment of the screw 44 which determines the maximum stroke of the arm.

After the diamond 21 has passed the work as above described the operation of the machine continues at a finishing feed until the second diamond 22 passes the work allowing the longer arms of the gage and circuit closer to move downward whereupon another circuit is closed by engagement of the contacts 24 and 24'. This circuit is the energizing circuit for the electromagnet 55 and includes conductors 53 and 54. When the electromagnet 55 is energized it lifts the pawl 42 out of engagement with the ratchet 41 and thus stops the feed. Detent pawl 45 being still in engagement with the ratchet holds it against reverse movement while the grinding wheel continues to travel back and forth producing a true surface and a high polish on the work.

The pawl 42 is provided with a contact 57 which engages adjacent terminals on a

pair of conductors 59 and 60 when the pawl is attracted by the electromagnet 55. This closes a circuit which includes the energizing coil of an electromagnet 58 and the electromagnet 58 thereupon attracts its armature 70 61 which consists of the enlarged head of a balanced piston valve 61'. This valve is slidably mounted in a casing 70 and may be positioned so as to admit oil from a feed pipe 62 through the casing to an outlet port 63 or else to permit it to escape by way of a port 68. When the valve is in position to admit pressure fluid through the port 63 the piston 64 will be raised in its cylinder 72 and this will act through the rod 64' and 80 a rockarm 45' to lift the detent 45 out of engagement with the ratchet 41, thereby permitting the weight 46 to return the ratchet to its original position by means of cable 47, thus backing the wheel away from the work. 85 Preferably the pawl 45 will be loosely connected to the rockarm 45' so as to provide the necessary lost position to permit it to slip over the teeth of the ratchet. The original movement of the piston 64 is relatively 90 slow, this speed being regulated by a valve (not shown) in the feed pipe 62. The slow movement allows time for the operation of finishing and polishing the work, as above referred to, and continues until the piston 95 passes the opening of the feed pipe 66 which is not restricted in its delivery of liquid to the cylinder 65 and therefore quickly raises piston 64 to disengage the detent 45.

The feed retarding weight 46 at the end 100 of its fall strikes a flat face on a bent lever 67 having forks at 67' engaging a pin on the stem of valve 61'. The momentum of the weight causes it to withdraw the head of the valve from the magnet 58 and moves 105 it into the position indicated in Figure 10 closing the feed pipe 62 and opening the exhaust port 68 to permit the pressure fluid to escape. The spring 69 in the casing 72 acts on the piston 64 to return it to the bottom of its casing this spring being strong enough to overcome the pressure of the oil in pipe 66 and to force the oil out through ports 63 and 68. When the piston reaches its original position it cuts off the 110 flow from pipe 66 as shown in Fig. 10.

An adjustable stop 71 (Fig. 10) is positioned to limit the movement of the lever 67 under the impetus given to it by the weight 46. This stop 71 has a stem 71' 115 slidably mounted in a bracket 72' on a fixed part of the machine frame. A set screw 73 serves to hold the stem in adjusted position. This device prevents damage to the valve in that it prevents the full force of 120 the weight from being transmitted to the valve stem.

A port 74 is provided in the casing 72 back of the piston to drain off any oil that might get back of the piston and interfere 125

with its movement, this port being connected to the exhaust in suitable manner by a pipe 72'. An exhaust port 75 is also provided in the valve casing 70 to exhaust any oil 5 which may get back of the piston 61' and thus might interfere with its movement.

A signaling device 76 here shown as an electric light but which may take the form of an audible or other signal is shown as 10 interposed in the conductor 59 in Fig. 9. This is shown for convenience as if it were suspended on the conductor but ordinarily will be mounted on a fixed support such as the frame member 40 (Fig. 8).

15 The operation of the device may be briefly described as comprising six steps or stages, the first step being that in which the wheel is fed in rapidly while grinding the work roughly to size. The second step is that 20 during which the wheel is fed in slowly to finish the grinding. The third step is that in which the wheel is not fed in but the relative traverse of the wheel and the work continues as well as their relative rotation. 25 During this time a finish or polish is given to the work. The fourth step is that in which the wheel backs away to provide room for changing the work. The foregoing steps take place automatically and as the fifth 30 step the operator is notified by a signal that the operation is complete, such a signal being here indicated as being given by a light. The sixth step, which is the only manual one, consists in retracting the foot stock by 35 means of the lever 34, thus simultaneously breaking the circuits and bringing the diamonds to a low point below the position indicated in Figure 5. A new piece of work is now placed between the centers and the 40 operation is repeated. As above explained the gage may at once be released from the hook 29 or may be left there until the work has been ground sufficiently to provide a 45 smooth surface for the engagement of the first diamond.

It will be obvious to those skilled in the art that various changes may be made in my device without departing from the spirit of the invention and therefore I do not limit 50 myself to what is shown in the drawings and described in the specification but only as indicated in the appended claims.

Having thus fully described my said invention, what I claim as new and desire to 55 secure by Letters Patent, is:

1. In a grinding machine, a wheel, a rotary workholder, a diameter gage having an arm swingable on a pivot parallel to the axes of the wheel and the workholder said arm 60 being longer than the distance between its pivot and the unfinished work and being biased to move past said work, means for retracting a work center to release the work, and connections therefrom to move the gage

into idle position remote from the work, substantially as set forth. 65

2. In a grinding machine, a wheel, a rotary workholder, a diameter gage having an arm swingable on a pivot parallel to the axes of the wheel and the workholder said 70 arm being longer than the distance between its pivot and the unfinished work and being biased to move past said work, means for retracting a work center to release the work, connections therefrom for moving the gage 75 into idle position remote from the work, and means whereby the gage may be moved into such position independently of such retracting means, substantially as set forth.

3. In a grinding machine, a wheel and a 80 workholder, traversing means for one of said devices, means for feeding one toward the other for a roughing cut, means to reduce the rate of feed for a finishing cut, means to stop the feed while continuing the traversing movement to polish the work, and means thereafter to move one of said devices away from the other, substantially as set forth. 85

4. In a grinding machine, an abrading device, a workholder, means for feeding one toward the other, means for stopping the feed including a ratchet, an operating pawl therefor, a gage for the work, connections from the gage to the pawl for disconnecting it from the ratchet at a predetermined time, 90 a detent for the ratchet, means for withdrawing the detent from the ratchet upon completion of the grinding operation including a fluid motor, means operated on disconnection of said operating pawl for admitting fluid pressure to said motor, and means acting upon withdrawal of said detent to space the abrading device from the workholder, substantially as set forth. 95

5. A grinding machine as in claim 4, said means for spacing the abrading device from the workholder comprising a disk fixed to said ratchet, a cable passing about said disk, and a weight on said cord, substantially as 100 set forth. 110

6. A grinding machine as in claim 4, having a valve controlling said fluid pressure, a lever for operating the valve, a disk fixed to said ratchet, a cable passing about said disk, and a weight on the cable for turning the ratchet backward to space the abrading device from the workholder said valve-operating lever being in the path of said weight, substantially as set forth. 115

7. In a grinding machine, an abrading device, a workholder, means for feeding one toward the other, means for stopping the feed including a ratchet, an operating pawl therefor, a gage for the work, connections from the gage to the pawl for disconnecting it from the ratchet at a predetermined time, 120 a detent for the ratchet, means for withdrawing the detent from the ratchet upon com- 125

pletion of the grinding operation, and means operated on withdrawal of said detent to space the abrading means from the workholder, substantially as set forth.

8. In a grinding machine, an abrading device, a workholder, means for feeding one toward the other, means for stopping the feed including a ratchet, an operating pawl therefor, a gage for the work, connections from the gage to the pawl for disconnecting it from the ratchet at a predetermined time, a detent for the ratchet, means for withdrawing the detent from the ratchet upon completion of the grinding operation including a fluid motor, means operated on disconnection of said operating pawl for admitting fluid pressure to said motor with a delayed action whereby the abrading device may polish the work while the feeding operation is intermittent, and means acting on withdrawal of the detent to space the abrading device from the workholder, substantially as set forth.

9. A grinding machine as in claim 4, said connections from the gage to the operating pawl including a normally-open electric circuit, an electromagnet for the pawl in said

circuit, a second normally-open circuit, a contact on the pawl for closing the second circuit, an electromagnet in the circuit, a valve to admit pressure fluid to the fluid motor, and a part on said valve serving as an armature for the second electromagnet, substantially as set forth.

10. A grinding machine as in claim 8, with a valve for reducing the fluid pressure, means acting to close said valve after said spacing operation, and means to return the movable element of said fluid motor upon reduction of such pressure, substantially as set forth.

11. In a grinding machine, a wheel and a workholder, means including a gravity-operated gage controlled by the size of the work for feeding one toward the other for a roughing cut, means operated by said gage to reduce the rate of feed for a finishing cut, means to polish the work, and means thereafter to move one of said devices away from the other, substantially as set forth.

In witness whereof, I have hereunto set my hand at Waynesboro, Pennsylvania this 5th day of May, A. D. nineteen hundred and twenty-five.

AMOS P. STEINER.
